HERBERT POMFRET, OF LOS ANGELES, CALIFORNIA.

CONCRETE-BUILDER'S AGGREGATE SUPPORT.

Application filed August 11, 1925. Serial No. 49,555.

To all whom it may concern:

Be it known that I, HERBERT POMFRET, a citizen of Australia, residing at Los Angeles, in the county of Los Angeles and State of California, have invented a new and useful Concrete-Builder's Aggregate Support, of which the following is a specification.

In monolithic buildings the concrete floors are supported by beams and beam supported joists which extend from beam to beam at right angles thereto; all three elements constituting a monolithic part of the structure; and in order to temporarily support the aggregate for the floor, joists and beams, the builder employs temporary wooden beam forms, and metallic pans consisting of U-shaped sheet metal trough-like bodies; and such bodies are made of different depths, and their walls are temporarily nailed to wooden joists that extend across the entire space between, and jam against the sides of the beam forms in order to confine and support the aggregate of which the floors, joists and beams are to be made.

The beams are molded in trough-like temporary structures comprising beam-sides and soffits extending from column to column of the building and supported by transverse caps a few inches longer than the width of the trough formed by the soffits and the beam-sides; said caps being supported by shores supported by releasing wedges which in turn are supported by planks laid on the ground or on a floor below the floor to be constructed.

Near the upper edges of the beam-sides, ribbons are nailed to support the temporary wooden joists, and on these ribbons the ends of joists are laid to support the pans, or the temporary decking, which is equivalent thereto. Such ribbons are usually one by six inch boards.

The concrete joists of different buildings are of various depths according to the purpose of the engineer; and where the ribbon is used, it is not possible, without additions to the form or a loss of concrete, to use pans having a depth so great as to extend below the bottom of the temporary wooden joists that rest upon the ribbons.

When the pans are of such depth that they must extend below the bottom of the joists that support them, the ribbons interfere with bringing the ends of the pan

jam against the beam-sides, and therefore open spaces are left between the wooden joists, the beam-sides and the ends of the pans, and such spaces must be filled in some manner as by strips of wood, to prevent the aggregate from falling through.

An object of this invention is to make provision whereby the ribbon may be dispensed with, thus allowing the sheet metal pans to be extended below the wooden joists when necessary, and yet allowing their ends to normally fit jam against the beam-sides; thus allowing the use of deep pans for molding concrete joists and slabs in cases where the pans are so deep relative to the concrete joists, that their edges must extend below the bottom of the wooden joists to which they are nailed or otherwise secured.

An object is to eliminate the ribbon and the time, labor and material heretofore necessary in order to use such pans when they are so deep as to extend below the temporary joists.

An object of this invention is to provide brackets which will support the temporary joists without likelihood of crushing the beam-side and to combine therewith temporary wooden joists in such a manner that the workman erecting the temporary form will be enabled, without measuring, to invariably place the temporary joists in position properly centered on the bracket. In this respect the beam-sides are constructed with cleats of a width not to exceed the width of the joists; and the brackets are formed of bent metal plates of sufficient thickness to support, with a high coefficient of safety, the weight to which they are to be subjected, and such brackets are fastened to the beam-sides and are centered with respect to the cleats; and I have provided a central tooth on the bracket to enter saw-kerfs in the ends of the joists when the joists are in place.

The invention includes the beam-sides provided with the narrow brackets thereon, and the combination of the beam-sides, the brackets and joists hereinafter set forth and claimed, and the specific construction of joist supporting bracket which will herein-after be described and claimed.

Superior strength of the temporary form, and ease of erecting and disassembling it are further objects of the invention.

Objects of this invention are to save labor and nails in building such false work, and to preserve for subsequent use the lumber employed in such false work; to save concrete; to facilitate proper placing of the pans and to facilitate removal of the false work after the concrete beams, ceiling and floor have set.

The beam-sides are usually constructed of 10 horizontal boards fastened together by vertical cleats and such cleats are of any width determined upon by the builder, and are usually terminated below the top of the beam-side just the thickness of a temporary joist; and such joist rests thereon.

The ribbons above referred to are nailed on the cleats with their upper edges flush with the upper ends of the cleats, and the joists are made to rest on both the cleats 20 and the ribbons. Such construction causes the difficulties above outlined.

An object of this invention is to avoid such difficulties.

This invention comprises a novel beam-side for use in moulding the sides of beams in concrete structures and such novel beam-side is provided with brackets adapted to support the ends of the temporary joists and not exceeding in width, the width of such joists, so as to allow the pans to be fixed to the sides of the temporary joists and extend therebelow and yet be brought jam against the beam-side that supports the joists, for supporting the pans or the decking for the floor to be moulded.

In this invention I eliminate the ribbons and provide brackets extending over the cleats to support temporary joists, and I make these brackets of a width not exceeding the width of the temporary joists.

A further object of the invention is to provide a simple and effective bracket which can be placed at different positions along the beam-side to accommodate the different spaces of the temporary joists.

A further advantage secured by this invention is the certain support for the beam-sides which is secured by the brackets arranged to hold the beam-sides against the lateral pressure of the aggregate while the beams are being molded.

An important advantage gained by this invention arises from striking up from the joist supporting ledge of a sheet metal bracket, a tooth extending transversely of the ledge so as to enter a longitudinal saw kerf in the end of a joist, and by so forming the tooth the same becomes a fixed part of the bracket and the joist is held in place by simply seating it on the ledge and seating the tooth in the joist; and by this simple means I secure the required stability and economize the time of the workman that sets up the work since he is not required to handle or drive any nails; and the work of

stripping the joists is simplified and there is no waste of material and a great economy of time is effected through this arrangement.

Other objects, advantages and features of invention may appear from the accompanying drawing, the subjoined detailed description and the appended claims.

The accompanying drawing illustrates the invention.

Figure 1 is a perspective view of a bracket constructed in accordance with this invention.

Fig. 2 is a section of a fragment of a beam-side and bracket on a plane indicated by line x^2 , Fig. 1.

Fig. 3 is a perspective view of another form of the bracket.

Fig. 4 is an elevation illustrating the use of the bracket in building a concrete structure, fragments of which are shown in vertical section on different planes.

Fig. 5 is a fragmental elevation in vertical section at right angles to Fig. 4 on line x^3 , further illustrating the use of the invention in concrete construction.

The bracket a consists of a plate comprising an intermediate upright member 1 provided with an upper hook 2, a lower ledge 3 and a down-turned temporary work holder 4. The hook is shown as provided at 5 with a hole forming a retainer by which the bracket may be secured to the temporary work as by means of a nail or the like, driven through the hook into the beam-side; and the ledge 3 is likewise shown with a retainer for the same purpose, and adapted to engage the temporary joist.

Said retainers may be in the form of perforations 5 and 6, and nails may be driven through said perforations into the temporary work to fix the bracket to such work.

In Fig. 1 the ledge is also shown with a retainer formed of a tooth 7, which is stamped up at an angle of 90° from the ledge 3 as indicated by the hole 8 from which said tooth has been stamped in Fig. 1.

The form of the blank plate from which the bracket shown in Fig. 1, is bent up will be understood from Figs. 1, 2 and 3, by those skilled in the art. The struck up tooth 7 is preferably a right angle triangle as indicated in Figs. 1 and 3, and the perpendicular of such tooth fits snugly against the upright face of the intermediate member 1 of the bracket, and a bracket thus formed is adapted to maximum strength with minimum structure.

A. The sheet metal pans are usually made in sections, the intermediate sections being opened, end troughs, and the sections having one end closed to fit against the beam-sides and forming practical upward continuation thereof to retain the aggregate above the beam-sides and to give form to the concrete beam between the concrete joist.

The pans 9 to support the concrete are usually supported by temporary wooden work such as the shores 10, cap 11, braces 12, beam soffit 13, beam-sides 14 with cleats 15 and temporary wooden joists 16; the shores being supported by releasing wedges 6 on the plank *c* laid on the foundation or floor *d* below; and the beam-sides and joists serving to support the pans 9.

- 10 The joists 16 are supported by the brackets *a* in the following manner. The hooks 2 are seated on top of the beam-sides of the temporary work and the temporary joists 16 are seated on the ledges 3. If nails are used 15 to fix the hook and ledge in place, they are driven through the retaining holes and into the temporary work with the downward extensions of the ledge against the faces of the cleats as in Fig. 4, or against any other part 20 serving a like purpose.

The bracket thus serves the double purpose of supporting the horizontal joist, and retaining the top of the beam-side against lateral pressure of the aggregate.

- 25 In case the tooth 7 has been struck up from the plate, transversely to the ledge, in forming the bracket, the ends of the joist will be provided with saw-kerfs 17, which will receive the teeth 7 in assembling the 30 temporary wooden work.

When such work is thus supported the pans 9 or the aggregate or equivalent decking 18 will be brought into place to support the concrete 19 in the usual way.

- 35 The downwardly extending temporary work holder or retaining means 4 support the tops of the cleats; and the lower ends of the cleats are supported against lateral pressure of the aggregate in the usual way 40 by blocks 20 nailed onto the caps.

After the concrete forming the beams 21 or the slabs 22 is fully cured, the temporary work may be easily removed by taking down the beam-sides with the brackets.

- 45 I claim:

1. A concrete builder's pan support, comprising a beam molding form having beam-sides provided with upright cleats and with brackets adapted to support temporary joists; said brackets and cleats being of less 50 width than the joists for the purpose of allowing the concrete builder's pans, when fastened to the temporary joists, to extend below the temporary joists and to be brought 55 jam against the beam-sides.

2. The combination with a temporary concrete builder's pan supporting joist, of a beam-side provided with an upright cleat to extend under an end of a temporary beam supporting joist, and a bracket on said cleat of a width no greater than the joist supporting said bracket, being adapted and arranged to support an end of the temporary joist for supporting the pans.

3. A beam-side for concrete builders, pro-

vided with a bracket consisting of a vertical body member, a hook at the upper part of said member to rest on the top of a beam-side, and a ledge at the bottom of said member provided with an upwardly extending fixed tooth to engage a temporary joist.

4. The bracket for a beam-side having an upright cleat, said bracket being a metallic plate bent at its upper end to form a hook and at its lower end to form a ledge and having a lip extending down from said ledge for the purpose of supporting the beam-side against outer pressure.

5. The bracket for a beam-side having an upright cleat; said bracket being a metallic plate bent at its upper end to form a hook and at its lower end to form a ledge, said ledge also being provided with a tooth struck up from the ledge and extending transversely thereto for the purpose of engaging the end of a joist.

6. The combination with a beam-side and a temporary joist having a central saw-kerf in the end; of a bracket provided with an intermediate member, a hook at the top of the member, a ledge at the bottom of the member and a tooth struck up centrally from said ledge to be seated in the saw-kerf when the joist is on the ledge.

7. The combination with a beam-side and a temporary joist having a saw-kerf in its end; of a bracket consisting of a plate not exceeding in width the thickness of the joist and consisting of an intermediate member, a hook at the top of said member, a ledge at the bottom of said member and a tooth struck up from the ledge, and adapted to be seated in the saw-kerf when the joist is placed on the ledge.

8. The concrete builder's bracket set forth comprising a bent plate having an upright intermediate member, a hook at the top, and projecting from one face of the intermediate member, a ledge at the bottom and projecting from the other face of the intermediate member, and retaining means extending downward from the ledge.

9. The concrete builder's bracket set forth comprising a bent plate having an upright intermediate member; a hook at the top of the intermediate member; a ledge at the bottom of the intermediate member; and retaining means extending downward from the ledge, said ledge and hook being provided with means for securing the same to temporary work.

10. The concrete builder's bracket set forth comprising a bent plate having an upright intermediate member; a hook at the top of the intermediate member; a ledge at the bottom of the intermediate member; and retaining means extending downward from the ledge; the ledge being provided with an upwardly extending tooth to engage temporary work.

11. A bracket having an upright intermediate member, a hook at the top of the intermediate member, a ledge at the bottom of the intermediate member, and a tooth struck up from the ledge and adapted to be inserted into the end of a joist supported by the ledge.
12. A bracket comprising a bent plate having an upright intermediate member, a

hook at the top of the intermediate member, a ledge at the bottom of the intermediate member; and a triangular tooth struck up from the ledge with its perpendicular against the upright intermediate member.

In testimony whereof, I have hereunto set my hand at Los Angeles, California, this 4th day of August, 1925.

HERBERT POMFRET.
